MAX F. MANGELSDORFF, OF NEW YORK, N. Y., ASSIGNOR TO COMBUSTION UTILITIES COMPANY, OF NEW YORK, N. Y., A CORPORATION OF NEW YORK.

FUEL-BURNER FOR CEMENT-KILNS.

977,113.

Specification of Letters Patent. Patented Nov. 29, 1910.

Application filed April 7, 1906. Serial No. 310,574.

To all whom it may concern:

Be it known that I, MAX F. MANGELSDORFF, a citizen of the United States, and resident of New York, in the county of New York and State of New York, have invented a certain new and useful Fuel-Burner for Cement-Kilns, of which the following is a specification.

This invention relates to fuel burners for cement kilns and consists in a device for injecting powdered fuel with air and feeding auxiliary air to the jet so formed in order to produce a positive, regulable flame suitable for heating rotary cement kilns, such as are employed for burning Portland cement and for like purposes; all as more fully hereinafter set forth and as claimed.

In the modern practice of cement burning the dry material, which is a mixture of clay and limestone, artificially or naturally admixed, is progressively advanced through a rotating inclined kiln, lined with refractory materials, in heating relation to a flame burning in the mouth of the kiln. This flame must afford temperature enough to frit or sinter the clay component of the cement mixture, since otherwise it would not enter into the clinker-making reaction with the lime from the limestone, but it must not injure the refractory material of the lining, which is generally fireclay. It is obvious that a nice regulation of temperature is requisite to meet these requirements.

Powdered coal burning in aerial suspension is one of the few cheap and available fuels which will yield the necessary temperature for clinker-making, but unfortunately it also yields rather more, making it dangerous to kiln linings unless the flame be under thorough control. It is the purpose of the present invention to provide a powdered coal flame which shall be under such thorough control and which shall produce a safe but powerful clinkering action.

In the present practice, it is the custom to inject the coal dust with only a few per cent. of the air necessary to burn it, depending upon the draft of the kiln to furnish the residue. There are several reasons for this practice, one being that a mixture of coal dust with the full amount of air of course furnishes an explosive body and should the rate of feed through the burner nozzle temporarily fall below the backward rate of flame propagation, dangerous explosions

might result; another being that it is difficult to suspend coal evenly and uniformly throughout such an amount of air, and still a third being that the air currents entering through the mouth of the kiln are relied upon to form a relatively cold sheath about the flame, spacing it away from the kiln walls and material thereon and obviating danger from the unduly hot flame produced from the ordinary round jet nozzle. In the present invention, I depart from this practice and while feeding in the coal dust directly with only a limited, safe amount of air, I inject into, and carry the flame plume by, the rest of the air in the form of auxiliary jets substantially parallel thereto.

In the accompanying illustration, I have shown certain forms of apparatus within my invention for accomplishing the described objects. In this showing:

Figure 1 is a plan view of one embodiment of my invention; Fig. 2 is an end elevation of the same structure, showing the cross-sectional relationship of the elements; Fig. 3 is a plan view of a modification; Fig. 4 is a similar end elevation of the structure of Fig. 3; Fig. 5 is a plan view of another modification; Fig. 6 is an end elevation of Fig. 5; Fig. 7 is a longitudinal elevation of another modification; and Fig. 8 is an end elevation of the same.

Like reference characters are employed for like elements throughout the showing.

The main air supply trunk, 1, is connected with a suitable source of air, or of air mixed with products of combustion in case it is desirable to temper the coal flame.

2 and 2' are blast nozzles communicating with the air trunk and opening into the discharge pipes 4 and 4', directly beneath the hoppers 3 and 3' for powdered fuel. 5 and 5' are auxiliary air pipes also connected to the air trunk, but unprovided with coal hoppers or nozzles. They discharge air in a direction parallel to the discharge from the air-coal pipes.

In Figs. 1, 3 and 5 the discharge pipes and auxiliary air pipes terminate in a mixing chamber, which may have various shapes according to the amount or character of the mixture of the various jets to be made in it. In Fig. 1, the chamber has parallel or slightly tapering sides and is so constructed that the open end shall have the same area as the area of cross-section of pipes 4, 5 and

5'. This results in the coal-charged air jet and the other air jets flowing out of the end of the chamber in substantially parallel lines. As the air in 5 and 5' does not pass 5 through a nozzle or carry coal, it will emerge with a greater velocity than that from discharge pipe 4, other conditions being equal, and will entrain it. As shown, the mixing or nozzle chamber 6 has a flattened 10 opening and will produce a flattened flame of less localized intensity in any one part than will the ordinary round jet nozzle. In Fig. 3, the two outer pipes carry coal while the free air pipe is between them. The 15 burner nozzle, as shown, has a slight outward flare which contributes materially to the formation of a flattened flame. In both the figures, the construction of the burner nozzle is such that the air currents will still 20 preserve substantial parallelism beyond the opening thereof, the swifter moving air jet helping to carry forward the coal laden jet. In Fig. 5, the nozzle chamber is provided with a constriction 8 which assists in 25 perfecting the contacting of the two classes of jets prior to their emergence from the nozzle.

In Figs. 7 and 8 a similar construction is shown provided with a dead plate 7 in order 30 to provide for a spreading of the flame.

The higher velocity of the air jet causes it to act inductively on the slower moving coal jet, assisting in carrying forward the fuel, and the two together act to form a 35 positive flame, easily directed and shifted and easily controllable as to length and impingement. To produce these results it is substantially necessary that the two classes of jet should be, as shown, practically parallel.

What I claim is:—

1. A flat-flame burner for cement kilns comprising a source of air under pressure, a flattened nozzle chamber having an unrestricted, full-area flame outlet, a coal-jet conduit connected to said source and ending at and communicating with the nozzle chamber, means for discharging powdered coal into said pipe, and an air conduit, also con-

nected to said source and ending within said 50 chamber, adapted to form an air jet parallel to and contacting with the air-coal jet coming from the first-named conduit, the shape of the nozzle chamber and flame-outlet being such as to produce a flattened 55 flame and maintain the separate existence of the several jets.

2. A flat-flame burner for cement kilns comprising a source of air under pressure, a flattened nozzle chamber having a flattened, unrestricted, full-area flame outlet, a coal-jet conduit connected to said source and ending at and communicating with the nozzle chamber, means for feeding powdered coal into said pipe, and an air conduit, also 60 connected to said source and ending within said chamber, adapted to form an air jet parallel to and contacting with the air-coal jet coming from the first-named conduit, the shape of said nozzle chamber and flame 65 outlet being such as to produce a flattened 70 flame and maintain the separate existence of the several jets.

3. A flat-flame burner for cement kilns comprising a source of air under pressure, 75 a nozzle chamber of a flattened shape with a median constriction and having a flattened, full-area flame outlet, a coal-jet conduit connected to said source and ending within the nozzle chamber behind said constriction, means for feeding powdered coal into said pipe, and an air conduit, also connected to said source and ending within the chamber behind the constriction, adapted to 80 form an air jet parallel to and contacting with the air-coal jet coming from the first-named conduit, the shape of said nozzle 85 chamber and flame outlet being such as to produce a flattened flame and maintain the separate existence of the several jets.

Signed at New York in the county of New York and State of New York this 5th day of April A. D. 1906.

MAX F. MANGELSDORFF.
